UNITED STATES PATENT OFFICE

GEORGE J. STROESSER AND FRED MEDER, OF MILWAUKEE, WISCONSIN; SAID MEDER
ASSIGNOR TO SAID STROESSER

GOLF-BAG STAND

Application filed September 28, 1927. Serial No. 222 621.

Our invention relates to improvements in golf bag stands.

The object of our invention is to provide a light, collapsible, easily constructed golf bag support which may be quickly secured to any 5 golf club bag.

It is another object of our invention to provide a golf bag support which will easily be collapsed against the body of the golf 10 bag to facilitate carrying the bag from place to place.

It is a further object of our invention to provide a detachable golf bag stand which will be receivable into the golf bag for storage, or transportation to and from the golf 15 links.

In the drawings:

Figure 1 is a side view of a golf club bag equipped with our stand and supported in 20 operative position.

Figure 2 is a front view of the same bag and our improved stand.

Figure 3 is a detailed side view of the principal parts of our construction.

25 Figure 4 shows the spring mounting for the legs of our stand.

Figure 5 is a section on line 5—5 of Figure 3.

Figure 6 is a detail of the spring device 30 for control of the clip.

Figure 7 shows the method of securing the chain about the bag.

Like parts are identified by the same reference characters throughout the several 35 views.

Our device for supporting a golf club bag 1 is assembled entirely upon a comparatively small plate 2 which is provided with a hook 3 adapted to extend over the top of the bag 40 and down into the inside as indicated in Figures 1 and 3. A spring plate 4 secured to the inner face of plate 2 presses against the outside of the top of the bag to clamp the bag in the hook.

45 At one side of the lower end of the plate 2 a ball bead chain 5 is secured as indicated at 6. This chain is provided to secure the plate 2 to the bag by wrapping the chain about the bag and by snapping it into a slot 50 7 opposite the point 6 at the other side of

plate 2. Obviously any bag, of any size may be secured to the plate in this manner for the adjustment is variable to any reasonable degree desired.

The remaining structure comprising our 55 device concerns the legs and means for controlling them. We have provided two legs for this purpose although obviously a single leg with a broad foot at the bottom thereof, or more than two legs could be operated in 60 a manner similar to that now to be described. Each of the legs 8 and 9 is connected pivotally to the plate 2 at 10 and 11, respectively, each leg having a spring metal shank 12 between the pivotal connection and the 65 wood or other light weight material of which the legs are made. These metal shanks are so sprung as to normally draw the legs 8 and 9 closely together in parallel relation in all positions of the legs about their respective 70 pivotal connections 10, however, the clip 13 mounted pivotally upon a horizontal axis at 14 is provided to guide the legs to a spread position for supporting the bag as follows:

When the bag is supported by the legs the 75 clip 13 is extended horizontally outwardly from the bag and the curves 16 of the clip perform their function of receiving and holding the legs so as to prevent them from collapsing against the bag or extending themselves too far away from it. These curves are formed in the clip at the correct point to give the legs the correct angle for maximum stability coincident with easy use of the bag by its owner.

85 When the bag is to be carried by its handle 16 downward pressure upon the curved end 14 of the clip 13 will compress the clip wire and permit the legs to snap out of their position as shown in Figures 1 to 5 and to assume a position contiguous to the bag where the clip by reason of the influence of a spring 7 will press the legs tightly against the bag until they are again needed.

In actual use little attention need be paid 95 to the device, for the user can set up the bag merely by bringing the legs 8 and 7 in contact with the ground and by pulling the bag away from the legs until the clip snaps itself in place. When the next move is made 100

the bag is merely thrust toward the legs and the clip will snap the legs back toward the bag and hold them there. Obviously, the spring metal 12 of the leg shanks will hold the legs together beneath the clip and when the bag is set up the clip will maintain them in spread position to provide 3 point support for the bag.

We claim:

- 10 1. A device of the character described comprising a plurality of legs, spring shanks for the legs, a plate, and a clip pivotally secured to the plate and mounted thereon between the shanks for controlling and directing the motion of the legs about the pivots.
- 15 2. A golf bag support comprising legs provided with flexible shanks, a plate secured to said shanks, a hook and a chain for holding the plate to a golf bag, and a clip for limiting relative movement between the plate and the legs, said clip being pivotally secured to the plate and extending between said legs and being provided with arcuate portions partially encircling the legs.
- 20 3. The combination with a golf bag, of a plate provided with a hook and a spring between the plate and the hook, a chain adjustably connected with the plate and adapted to encircle the bag, legs pivotally secured to the plate, and a clip for guiding the legs in pivotal movement to and from the plate and for limiting said movement, said clip being extended between the legs and having portions extending transversely across the legs.
- 25 4. A golf bag support including a plate, legs pivotally mounted thereon for movement between a parallel relation adjacent the plate and a divergent relation at an angle from the plate, and a clip for controlling said pivotal movement, said clip being pivotally mounted on the plate and having portions extending transversely across the legs.

GEORGE J. STROESSER.

FRED MEDER.
